US00D830664S

(12) **United States Design Patent**
Van Wingerden

(10) **Patent No.:** **US D830,664 S**
(45) **Date of Patent:** **** Oct. 9, 2018**

(54) **ENGAGEMENT DEVICE FOR A
HYDROPONIC GROWING SYSTEM**

(71) Applicant: **Johannes Cornelious Van Wingerden**,
Stevensburg, VA (US)

(72) Inventor: **Johannes Cornelious Van Wingerden**,
Stevensburg, VA (US)

(**) Term: **15 Years**

(21) Appl. No.: **29/598,976**

(22) Filed: **Mar. 30, 2017**

(51) LOC (11) Cl. **15-09**

(52) U.S. Cl.

USPC **D99/99; D11/143**

(58) **Field of Classification Search**

USPC **D99/99; 264/401; 269/117; D8/381;
D13/102**

See application file for complete search history.

CLAIM

The ornamental design for an engagement device for a
hydroponic growing system, as shown and described.

DESCRIPTION

FIG. 1 is a perspective view of my design for an engagement
device for a hydroponic growing system;

FIG. 2 is a front side view of the design shown in FIG. 1;
FIG. 3 is a back side view of the design shown in FIG. 1;
FIG. 4 is a left side view of the design shown in FIG. 1;
FIG. 5 is a right side view of the design shown in FIG. 1;
FIG. 6 is a top view of the design shown in FIG. 1; and,
FIG. 7 is a bottom view of the design shown in FIG. 1.

1 Claim, 7 Drawing Sheets
